UNITED STATES PATENT OFFICE.

ARTHUR P. BAGBY AND JOHN B. THOMPSON, OF BIRMINGHAM, ALABAMA.

SAFETY ELEVATOR APPLIANCE.

1,302,623.

Specification of Letters Patent.

Patented May 6, 1919.

Application filed February 7, 1919. Serial No. 275,489.

To all whom it may concern:

Be it known that we, ARTHUR P. BAGBY and JOHN B. THOMPSON, citizens of the United States of America, residing at Birmingham, in the county of Jefferson and State of Alabama, have invented certain new and useful Improvements in Safety Elevator Appliances, of which the following is a specification.

10 Our invention relates to a safety appliance for elevators and has for its object to prevent the operation of an elevator when a landing door in its shaft is open.

More particularly it is our purpose to provide the elevator cab with a switch controlling the main circuit and with a counter-weighted carriage adapted to close the switch when a cam on the landing door has been moved to position with the door closed, 20 otherwise this cam will hold the carriage out of switch-closing position.

Our invention also involves the novel details of construction and arrangements of parts, which in their preferred embodiments 25 only are illustrated in the accompanying drawings, in which:—

Figure 1 illustrates our invention in front elevation.

Fig. 2 is a partial plan view of Fig. 1.

30 Figs. 3 and 4 are enlarged front and end elevations of the trolley and its correlated cam and switch.

Fig. 5 is a detail plan view enlarged of Fig. 3.

35 Similar reference numerals refer to similar parts throughout the drawings.

In the embodiment of our invention illustrated, each landing door 1 of the elevator shaft is provided with a cam 2 projecting above its upper end and preferably formed by a bent metal rod offset at top and bottom with a vertical intermediate section long enough to make provision for the ordinary variation in level at which the elevator may 45 be brought to rest at a landing. The elevator cab 3 may be of any construction and is provided on its top along the front edge with a straight horizontal track 4 formed by a metal bar supported at its ends by angle 50 brackets 5. On this track is mounted a carriage 6 formed of spaced plates connected at their four corners by pins on which rollers 7 turn. The rollers engage above and below the track which is interposed between the 55 plates, thus making provision against the carriage getting off its track. At its end

nearest the landing door the carriage is provided with a clip 8 to which is connected a cable 9 which passes over a sheave wheel 10 and is connected to a counter-weight 11 60 working in a pipe guide 12 on the side of the cab. The trolley is provided on its vertical face adjacent to the landing door with a pair of spaced bearing brackets 13 having journaled therein a shaft 14 which carries a stop plate 15, the latter being held at right angles to the trolley by a coil spring 16 surrounding the shaft and made fast at one end to the trip plate and at the other end to the trolley. In its lower portion an upwardly inclined plunger 17 is mounted having a fiber head 18 and having suitable guides 19 carried by the carriage. A coil spring 20 surrounds this plunger and bearing at one end against one of the brackets 75 and at the other end against a seat 21 on the plunger which forms a stop to limit its movement responsive to the spring. The fiber head of the plunger is disposed to engage the swinging door 22 of a circuit breaker 80 box 23, which door stands normally open with the switch open circuited and which, when engaged by the plunger, is thrust into its circuit closed position. The circuits thus controlled by this switch are illustrated in 85 Fig. 4 and comprise a lead 24 from the operator's switch 25, the circuit returning by lead 26 to the safety switch 27. When the switch 28 in the breaker box is open the main circuits controlling the cab are broken and 90 the elevator cannot be moved.

In operation, with the landing doors closed, the cams 2 are in position to be cleared by the trip plate 15 as the elevator runs and when it comes to rest opposite a landing and such landing door is opened, the cam on the latter will pick up the stop plate and run the carriage back on its track, thus permitting the breaker box switch to open. As the landing door is closed, the 100 counter-weight causes the carriage to follow along on its track after the cam until the plunger closes the breaker box switch and restores the current to the control of the operator. If the landing door is only partly 105 closed, the breaker box switch will not be closed and the car cannot be started. If the trip plate happens to strike any obstruction, being yieldingly pivoted to the carriage it will give and in like manner if the landing 110 door is closed too rapidly the yielding plunger will prevent injury to the breaker box

switch. The apparatus can be inexpensively installed, and is durable and reliable in its functioning.

This invention is not intended to be restricted in scope to the specific embodiments shown, but contemplates such modifications as come within the spirit and scope of the claims.

Having thus described our invention, 10 what we claim as new and desire to secure by Letters Patent, is:—

1. A device of the character described comprising a cam mounted on a landing door, a circuit breaker switch mounted on and adapted to control electrically the starting of an elevator cab, a switch closing carriage on the cab adapted to be engaged and moved with said cam as the door opens to open said switch, and means independent of 15 the door to urge said carriage to follow said door's closing movements and to close said switch when the door is fully closed.

2. A device of the character described comprising a cam movable with a landing 20 door, a circuit breaker switch adapted to control the starting of the car and which is mounted thereon, a switch closing carriage adapted to normally close said switch, and counter-weight means to urge the carriage 25 toward its switch closing position, said carriage being disposed in the path of and adapted to follow the movements of said cam.

3. In a safety elevator appliance, a landing 30 door carrying a cam, an elevator cab having a track thereon and a circuit breaker switch, a switch closing element movable along said track by the cam to open said switch, and a counterweight means to cause 35 said element to follow said door as it closes and to close said switch only when said landing door is fully closed.

4. In a safety elevator appliance, a landing 40 door carrying a cam, an elevator cab having a track and a carriage movable thereon and disposed in the path of the cam as it moves with the opening of the landing door, a circuit breaker switch, and counterweight means to normally force the carriage in the 45 direction to close said switch.

5. In a safety elevator appliance, a landing door carrying a cam, an elevator cab having a track and a carriage movable thereon, a circuit breaker switch, means to normally move the carriage to close said switch, 55 and means on a landing door disposed to clear said carriage as the cab moves when the door is closed and to engage and shift said carriage as the door opens to open said switch.

6. In combination, a landing door having a vertical double cam, an elevator having a transverse track, a carriage mounted on the track, a circuit breaker switch, a counter-weight adapted to move the carriage along 60 said track to close said switch, said cam being disposed to move the carriage reversely along said track to open said switch.

7. In combination, a landing door having an elongated cam rod projecting vertically 65 above it and bent at both ends to form reverse cams, an elevator cab having a circuit breaking switch, and a carriage adapted to close said switch and to clear said cam rod when the said door is closed and to be engaged and shifted by the cam as the door 70 opens to open said switch.

8. An elevator cab having a circuit breaker switch and a controller therefor comprising a bodily shiftable carriage having a spring plunger disposed to engage and close said switch, and means on the cab tending 75 to hold the carriage in switch closing position.

9. An elevator cab having a circuit breaker switch and a controller therefor comprising a bodily shiftable carriage having a spring plunger disposed to engage and close said switch, means on the cab tending 80 to hold the carriage in switch closing position, and means on a landing door to displace the carriage from switch closing position when the door opens.

In testimony whereof we affix our signatures.

ARTHUR P. BAGBY.
JOHN B. THOMPSON.
